RAILWAY TRAFFIC CONTROLLING
APPARATUSEarl M. Allen, Swissvale, Pa., assignor to The
Union Switch & Signal Company, Swissvale,
Pa., a corporation of PennsylvaniaApplication June 6, 1930, Serial No. 459,435
Renewed March 29, 1932

62 Claims. (Cl. 246—3)

My invention relates to railway traffic controlling apparatus for use on single track railroads over which traffic normally moves in both directions, and which are provided with passing sidings. More particularly, it relates to that class of systems wherein a despatcher located at a central office directs the movements of trains along the way by means of wayside signals or other devices, the despatcher carrying out the control of these wayside signals or other devices by means of selectively controlled relays located along the line.

The manner of controlling these relays located along the way may be as that of any of the well known systems such, for example, as disclosed in the Wallace Patent No. 1,650,575. The particular manner of controlling these relays form no part of this invention, and, for the sake of clearness, the control circuits therefor are not shown in the accompanying figures.

My invention resides in the manner of co-ordinating the wayside signals with the control exerted by the despatcher so as to bring about a unified traffic despatching system. The operation of such a unified system as here proposed allows a much greater freedom of train movements between sidings, without limiting the use of the track between the two points, than that permitted by present systems. This unified control is also obtained without the use of any line wires. While this system provides the well known A. P. B. signaling protection, it further provides the checking of the stop indication of the signals governing opposing movements.

I will describe one form of apparatus embodying my invention, and will then point out the novel features thereof in claims.

In Figs. 1^a and 1^b, when placed together with the right-hand end of Fig. 1^a adjacent the left-hand end of Fig. 1^b is shown a stretch of single track railroad extending from a passing siding P₁, shown at left-hand end of the Fig. 1^a, through a passing siding P₂ to a third passing siding P₃ shown at the right-hand end of Fig. 1^b. In the Figs. 1^a and 1^b is shown a preferred manner of locating the wayside signals, it being understood, however, that my invention is in no manner limited to this particular arrangement of signals, and furthermore, that any number of signals could be located between passing sidings. Figs. 2^a, 2^b, 2^c and 2^d, when placed end to end in the order named, constitute a diagrammatic view showing one arrangement of apparatus embodying my invention as applied to the wayside signals shown in Figs. 1^a and 1^b, and will be referred

to in this description as Fig. 2. Fig. 3 is a diagrammatic view of the track circuits only for a track section such as a track section V of Fig. 2. Fig. 4 is a diagrammatic view of the track circuits only for use in connection with a track section located between the opposite ends of a passing siding such, for example, as track section X of Fig. 2. Fig. 5 is a diagrammatic view of the track circuits only for a track section such as section W of Fig. 2. Fig. 6 is a diagrammatic view showing the control circuits only for relays associated with despatcher controlled signals such as signal R5.

In the Figs. 1^a and 1^b, the trackway is shown divided into sections, each section being equipped with signals for governing traffic in each direction. Each signal governing traffic from the left-hand end to the right-hand end is designated by the letter R with an exponent corresponding to the location. Each signal governing traffic from the right to the left is designated by the letter L with an exponent corresponding to the location.

These wayside signals may be of any of the well known types, and are designated here as of the colored light type. The despatcher controlled signals designated as R1, R5, R7, R11, L12, L8, L6 and L2 each have three signal mechanisms designated as A, B and C. Mechanism A is capable of displaying three indications "proceed", "caution", and "stop". The mechanism B, in the case of signals R5, R11, L8 and L2, is capable of displaying two indications "caution" and "stop". The mechanism B of the signals R1, R7, L12 and L6 is capable of displaying only a "stop" indication. The signal mechanism C is what is commonly called "call-on" signal and is capable of displaying two indications "call-on" and "stop". Signals R5, R11, L8 and L2 with their opposing automatic signals are preferably located approximately 1000 feet in advance of the facing point switch over which they govern train movements; it is to be understood, however, that this distance can be varied to suit the local conditions. The signals R1¹, R7¹, L12¹ and L6¹ which govern the train movements from the various sidings each have two mechanisms which are designated as D and E. The mechanism D is capable of displaying the three indications "proceed", "caution" and "stop". The mechanism E is a "call-on" signal and displays either a "call-on" signal or a "stop" signal.

In the Fig. 2, the traffic rails 1 and 2 are insulated into track sections by insulated joints designated by the reference character 3. In the

Fig. 2, each despatcher controlled relay is designated by the reference character HS prefixed by the reference character for the signal which this relay governs. For example, relay R5HS controls the signal mechanisms A and B of the signal R5. Each despatcher controlled relay governing a "call-on" signal is designated by the reference character CHS prefixed by the number designating the switch at which this relay is located. For example, relay 2CHS governs the call-on signals controlling the movements over the switch SW2. As stated above, the method of controlling these despatcher controlled relays forms no part of this invention. Suffice it to say, that, taking relay R5HS for an illustration, with the relay energized, the armatures 124, 231 and 232 are raised into contact with the front contacts 125, 233 and 234, respectively, while with the relay deenergized, these armatures drop into contact with their back contacts. All of the despatcher controlled relays of the system operate in a similar manner.

Each of the track sections is provided with a polarized track circuit. Referring to Fig. 4 in which is shown the track circuits for the section X of Fig. 2, it will be seen that at the right-hand end of the section a track relay TRX2 has one terminal connected to the rail 1 by conductor 348, back contact 341 of the despatcher controlled relay R7HS, armature 327, and conductor 342. The other terminal of this relay is connected to the rail 2 by conductor 343, back contact 344 of relay R7HS, armature 328 and conductor 345. At this same right-hand end of track section X, a track battery TB7 is connected to the rails 1 and 2 by the following circuit: battery TB7, conductor 14, back contact 15 of relay R7AH to be referred to later, armature 16, conductor 17, front contact 18 of relay R7HS, armature 328, conductor 345, rail 2, then across to rail 1, conductor 342, armature 327, front contact 24, conductor 23, armature 22, back contact 21, conductor 20 and back to the battery TB7. The positive terminal of battery TB7 may also be connected to rail 2 by a circuit consisting of conductor 26 branching off conductor 14, polar contact 37 of relay R7AH, polarized armature 33 in a position reversed to that shown in the figure, conductor 34, front contact 35, armature 16, conductor 17, front contact 18, armature 328, and conductor 345. The negative terminal of battery TB7 may also be connected to the rail 1 by a path consisting of conductor 31 branching from conductor 20, polar contact 36, polarized armature 28 reversed, conductor 29, front contact 30, armature 22, conductor 23, front contact 24, armature 327, and conductor 342. Furthermore, it is apparent that with the polarized armatures 28 and 33 of relay R7AH occupying the position as shown in the figure so as to be in contact with the polar contacts 27 and 32, respectively, the current supplied by the battery TB7 to the rails 1 and 2 is reversed in polarity. At the left-hand end of the section X, the track relay TRX1 is connected to the rails 1 and 2 of the track section X in a manner similar to that described in connection with relay TRX2. Relay TRX1 has one terminal connected to rail 1 by conductor 38, back contact 39 of the despatcher controlled relay L6HS, armature 40 and conductor 41. The other terminal of relay TRX1 is connected to rail 2 by conductor 42, back contact 43 of relay L6HS, armature 44 and conductor 45.

The track battery TB6 located at the left-hand end of section X has its positive terminal con-

nected to rail 2 by conductor 46, back contact 47 of a relay L6AH to be referred to later, armature 48, conductor 50, front contact 51 of the despatcher controlled relay L6HS, armature 44, and conductor 45. The negative terminal of battery TB6 is connected to rail 1 of section X by conductor 52, back contact 53 of relay L6AH, armature 54, conductor 55, front contact 56 of relay L6HS, armature 40, and conductor 41. The positive terminal of battery TB6 is also connected to rail 2 by the circuit including conductor 46, conductor 57, polar contact 49, polarized armature 64 reversed to its position opposite of that shown in the figure, conductor 65, front contact 66, armature 48 in a raised position, conductor 59, front contact 51, armature 44, and conductor 45. The negative terminal of track battery TB6 is connected to rail 1 by conductor 52, conductor 62, contact 67, polarized armature 59 reversed, conductor 60, front contact 61, armature 54, conductor 55, front contact 56 of relay L6HS, armature 40, and conductor 41. Furthermore, it is apparent that with the polarized armatures 59 and 64 in contact with the polar contacts 53 and 63, respectively, that the current supplied by the track battery TB6 to the rails 1 and 2 of section X is of reverse polarity. All track sections located between the opposite ends of a passing siding are to be equipped with track circuits similar to those just described in connection with the track section X of Fig. 4.

Referring now to Fig. 3, in which is shown the track circuits for the track section V of Fig. 2, it will be seen that the track relay TRV2 has one terminal connected to the rail 1 at the right-hand end of the section V by a conductor 346, back contact 347 of a relay R9S to be referred to later, armature 107, conductor 108, back contact 109 of the track relay TRU1 associated with the track section at the right of section V, armature 40 96, conductor 349, front contact 350 of a track relay TR9 associated with an insulating track section to be later described, armature 351, and conductor 97. The opposite terminal of the relay TRV2 is connected to the rail 2 by conductor 352, back contact 353 of relay R9S, armature 109, conductor 101, back contact 102 of relay TRU1, armature 103, conductor 354, front contact 355, armature 356, and conductor 104. At this same right-hand end of track section V, there is located the track battery TB9 which has its positive terminal connected to the rail 2 by a conductor 98, front contact 99 of relay R9S, armature 100, conductor 101, back contact 102, armature 103, conductor 354, contact 355, armature 356, and conductor 104. The negative terminal of the track battery TB9 is connected to the rail 1 by conductor 105, front contact 106 of relay R9S, armature 107, conductor 108, back contact 109 of relay TRU1, armature 96, conductor 349, front contact 350 of relay TR9, armature 351, and conductor 97. The positive terminal of battery TB9 is connected to rail 1 by a circuit consisting of conductor 94, front contact 95 of track relay TRU1, armature 96 in its raised position, conductor 349, front contact 350, armature 351, and conductor 97. The negative terminal of the track battery TB9 is connected to the rail 2 by a circuit consisting of conductor 110, front contact 111 of relay TRU1, armature 103 in its raised position, conductor 354, contact 355, armature 356, and conductor 104. At the left-hand end of the track section V, the track relay TRV1 is connected across the rails 1 and 2 at the left-hand end of the section V, with one terminal connected to 75

rail 1 by conductor 384, armature 385 of relay L8GP to be later described, conductor 386, back contact 387 of a despatcher controlled relay L8HS, armature 87, conductor 88, back contact 89 of a despatcher controlled relay 3CHS, armature 90, and conductor 91, while the other terminal of relay TRV1 is connected to rail 2 by conductor 380, armature 381, conductor 382, back contact 383 of relay L8HS, armature 75, conductor 76, back contact 77 of relay 3CHS, armature 78, and conductor 79. The track battery TB8 located at the left-hand end of track section V has its positive terminal connected to the rail 2 by either of two paths. First, conductor 70, back contact 71 of relay L8AH, armature 72, conductor 73, front contact 74 of the despatcher controlled relay L8HS, armature 75 to its raised position, conductor 76, back contact 77 of relay 3CHS, armature 78, and conductor 79. The second path branches from conductor 73 and extends along conductor 80, front contact 81 of the despatcher controlled relay 3CHS, armature 78, and conductor 79. The negative terminal of track battery TB8 is connected to the rail 2 by either of two paths. First, conductor 82, back contact 83 of relay L8AH, armature 84, conductor 85, front contact 86 of relay L8HS, armature 87, conductor 88, back contact 89, armature 90, and conductor 91. The second path branches from conductor 85 and extends along conductor 92, front contact 93 of the despatcher controlled relay 3CHS, armature 90, and conductor 91. Furthermore, it is apparent that with the armatures 72 and 84 of the relay L8AH raised into contact with the front contacts 25 and 19, respectively, that the current supplied by this track battery TB8 to the rails of the section V is reversed in polarity. All track sections of this system similarly located as the track section V are to be equipped with track circuits as shown in the Fig. 3, as just described.

In the Fig. 5 is shown the track circuits only for a track section adjacent the switch of a passing siding such as track section W of Fig. 2. At the right-hand end of the section W, the track relay TRW2 is connected across the rails by the conductors 358 and 359. At the left-hand end of the track section W, the track battery LB7¹ normally has its positive terminal connected to the rail 2 by conductor 360, back contact 361 of the track relay TRX2 associated with the track circuit X, armature 362, and conductor 363, and its negative terminal is normally connected to the rail 1 by conductor 368, back contact 369 of relay TRX2, armature 370, and conductor 371. The positive terminal of battery LB7¹ is also connected to rail 2 by a path branching from conductor 360 and extending along conductor 360¹, polar contact 364 of relay TRX2, polarized armature 365 reversed to its position opposite from that shown in the figure, conductor 366, front contact 367, armature 362, and conductor 363. Likewise the negative terminal of track battery LB7 is connected to the rail 1 by a path extending from conductor 368, polar contact 372, armature 374 of relay TRX2 in its reversed position, front contact 375, armature 370 in its raised position, and conductor 371. It is evident that with the relay TRX2 energized, so as to raise its neutral armatures 362 and 370, and its polarized armatures 365 and 374 occupying the position as shown in the figure, thereby making contact with contacts 376 and 377, respectively, that the current supplied by the track battery LB7¹ is reversed in polarity.

All track sections of the system similar to the track section W are to be equipped with track circuits similar to that described in reference to track section W.

Referring to the Fig. 2, at all intermediate signal locations, such as locations designated by the reference characters 9 and 10, a short insulated section is located between the two opposing automatic signals. This track section is preferably about 66 feet in length. This short insulated track section is provided with a track circuit consisting of a battery connected across the rails at one end of the section and a track relay connected across the rails at the opposite end.

Each of the despatcher controlled signals has 15 associated with it certain control relays. Referring to the Fig. 6, the despatcher controlled signal R5 has associated with it the control relays R5AH, R5BH and R5CH. The relay R5AH is associated with the signal mechanism A. The 20 relay R5BH is associated with the signal mechanism B, and the relay R5CH is associated with the signal mechanism C of signal R5. The circuit for the relay R5AH consists of the following 25 elements: battery LB6, conductors 144 and 120, front contact 121 of a relay L8GP, armature 122, conductor 123, armature 124 of the despatcher controlled relay R5HS, front contact 125, conductor 126, front contact 127 of the track relay TRX1 for the track section X, armature 128, conductor 129, polar contact 130 of a relay KR2 associated with the switch SW2 in a manner to be later described, polarized armature 131, conductor 132, armature 134, contact 135, conductor 136, contact 137 of the track relay TRY for the 30 section Y, armature 138, conductor 139, coils of the relay R5AH, conductor 140, armature 141 of the track relay for the section Z, back contact 142 and conductor 143 to the opposite terminal of the battery LB6. It is to be noted that to complete 35 this circuit for the relay R5AH that the despatcher controlled relay R5HS must be energized to close the contact 125, that the track relays TRX1 and TRY for the track circuits in advance 40 of the signal R5 must both be energized to close 45 the front contacts 127 and 137, respectively, and that the track relay TRZ2 for the track section in the rear must be deenergized to close the back contact 142. The circuits for energizing the relay R5BH consists of the following elements: battery 50 LB6, conductors 144 and 120, contact 121, armature 122, conductor 123, armature 124 of the despatcher controlled relay R5HS, front contact 125, conductor 126, conductor 157, polar contact 158, polarized armature 159 of the relay KR2 reversed to its position opposite from that shown in the figure, conductor 160, armature 161, front contact 162, conductor 163, contact 164 of the track relay TRY, armature 165, conductor 166, armature 167, back contact 168 of the relay 60 R5AH, conductor 169, coils of the relay R5BH, conductor 170, conductor 140, armature 141, back contact 142, and conductor 143 back to battery LB6. The circuit for energizing the relay R5CH consists of the following elements: battery LB6, 65 conductor 144, conductor 177, front contact 178 of the relay KR2, armature 179, conductor 180, front contact 181 of the despatcher controlled relay 2CHS, armature 182, conductor 183, armature 184 of relay R5AH, back contact 185, conductor 186, armature 187 of the relay R5BH, back contact 188, conductor 189, coils of the relay R5CH, conductors 190 and 143, armature 141, back contact 142 and conductor 143 to battery 70 LB6. 75

Referring now to Fig. 2, the relay KR2 associated with the switch SW2 is energized so that its armatures occupy the position shown in the figure by a circuit from positive battery to a circuit controller operated by the switch SW2, through the coils of the relay and back to the negative battery. With the switch SW2 reversed so as to reverse the position of the circuit controller associated therewith, then relay KR2 is energized so that its polarized armatures occupy the position opposite to that shown in the Fig. 2. It is therefore to be noted that with the switch SW2 set for main track movements, the circuit for the relay R5AH is held closed at the polar contact 130, of relay KR2, while with the switch SW2 set for movements for the passing siding then the circuit for the relay R5BH is held closed at the polar contact 158 of relay KR2. It is also to be noted that with the switch occupying either of its extreme positions, that the circuit for the relay R5CH is closed by the neutral armature 179 of the relay KR2. The relay R5GP is associated with the relays R5AH, R5BH and R5CH. The circuit for energizing this relay R5GP consists of the following elements: battery LB6, conductors 120, 144 and 197, armature 198 of relay R5AH, back contact 199, conductor 200, armature 201 of relay R5BH, back contact 202, conductor 203, armature 204 of relay R5CH, back contact 205, conductor 206, coils of the relay R5GP, and conductor 143 back to battery. That is to say, the relays R5AH, R5BH and R5CH must each be down before R5GP is energized. All despatcher control signals governing train movements approaching a passing siding have associated with them relays controlled in the same manner as just described in reference to Fig. 6, and each switch of this system has associated with it a circuit controller and a relay similar to that described in connection with the switch SW2.

Referring again to the Fig. 2, and looking at the despatcher controlled signal R7, it will be seen that this signal has associated with it the control relays R7AH and R7CH. The circuit for energizing the relay R7AH to operate its polar contacts to the left extends from the positive terminal of battery LB7 along conductor 210, back contact 211 of the track relay TRV1 for the track section V, armature 212, conductor 213, coil of the relay R7AH, conductor 208, polar contact 214 of relay KR3, polarized armature 215, front contact 217, armature 218, conductor 219, front contact 220 of the despatcher controlled relay R7HS, armature 221, conductor 222, armature 223 of the track relay TRW2, conductor 224, armature 225 of the relay R5GP, conductor 226, armature 227, back contact 228, and conductor 209 back to battery. With the track relay TRV1 energized and its armatures 212 and 227 raised into contact with the front contacts 229 and 230, respectively, then the current supplied by the battery LB7 to the relay R7AH is reversed in polarity to operate the polar contacts to the right, as shown. The circuit for energizing the R7CH relay extends from battery LB7 along conductors 210 and 249, armature 241 of relay KR3, conductor 242, front contact 243 of the despatcher controlled relay 3CHS, armature 244, conductor 245, polarized armature 246 of relay KR3, contact 247, conductor 248, armature 249 of relay R7AH, back contact 250, conductor 251, coils of relay R7CH, and conductor 252 back to battery LB7.

A signal R7¹ at the location 7 governs the traffic from the siding towards the right-hand end in Fig. 2. This signal R7¹ has associated with it the

control relays R7DH and R7EH. The circuit for energizing the relay R7DH consists of the battery LB7, conductor 210, back contact 211 of track relay TRV1, armature 212, conductor 213, conductor 270, coils of the relay R7DH, conductor 271, polar contact 272, polarized armature 215 when occupying position reversed to that shown, contact 217, armature 218, conductor 219, front contact 220 of a despatcher controlled relay R7HS, armature 221, conductor 222, armature 223, conductor 224, armature 225, conductor 226, armature 227, back contact 228, and conductor 209 back to battery. It is to be noted that the circuit for the control of this relay R7DH is the same as that traced for the relay R7AH except that the circuit for R7DH passes through the right-hand contact 272 of the relay KR3, whereas the circuit for the relay R7AH passes through the left-hand contact 214 of the relay KR3. The relay R7EH is energized over the following circuit: battery LB7, conductors 210 and 240, armature 241, conductor 242, front contact 243 of the despatcher controlled relay 3CHS, armature 244, conductor 245, polarized armature 246, right-hand contact 273 of relay KR3, conductor 274, armature 275, back contact 276, conductor 277, coils of the relay R7EH, conductors 278 and 252 back to battery. All signals governing train movements away from a passing siding are associated with control relays similar to those described in connection with the signals R7 and R7¹.

Each of the intermediate automatic signals is associated with a slow-releasing relay and a stick relay. Referring to the automatic signal R9 of Fig. 2, for example, the slow-releasing relay R9H is energized by the following circuit: battery LB9, conductor 231, armature 233 of the track relay TRU1 for the track section U in advance of the signal R9, front contact 295, conductor 296, coils of relay R9H, and conductor 297 to battery. The stick relay R9S associated with this signal R9 has the following pick-up circuit: battery LB9, conductor 237, armature 238 of track relay TRU1, back contact 298, conductor 299, armature 300 of the track relay TR9 for the short insulated section between the automatic signals R9 and L9, back contact 301, conductor 302, armature 303 of the stick relay L9S associated with the opposing automatic signal L9, back contact 304, conductor 305, armature 307 of the slow-releasing relay R9S, front contact 308, conductor 306, coils of the relay R9S, and conductors 236 and 297 to battery. The holding circuit for this stick relay R9S branches from the conductor 299 and extends along conductor 310, armature 311, its own front contact 312, conductors 313 and 306, coils of the relay R9S, back to battery.

Attention is here called to the control exerted by this stick relay R9S. It was described in connection with Fig. 3 that the connections of the track relay TRV2 to section V pass through the back contacts 347 and 353, and that the track battery TB9 is connected to the rails of section V through the front contacts 99 and 106 of R9S when the track relay TRU1 is down. It is to be noted that the polarity with which TB9 is thus connected to the section V is reversed to that prevailing when track relay TRU1 is up. It is to be understood that the polarity prevailing when relay TRU1 is up retains the polarized armatures of relay TRV1 in the position as shown in the Fig. 2. Therefore, with track relay TRU1 down and stick relay R9S up and the polarity of the current from TB9 reversed, then the polarized armatures of track relay TRV1 are reversed from the position as shown in Fig. 2.

Referring to the signal R5 in Fig. 2, the circuit for displaying a "proceed" signal extends from positive side of battery LB6 along conductors 120 and 144, armature 145 of the control relay R5AH, 5 front contact 146, conductor 147, armature 148 of the track relay TRY, front contact 149, polarized armature 150, right-hand contact 153, conductor 154, proceed light A¹ and to common battery. The circuit for displaying a "caution" signal is the same as that just traced for the "proceed" signal up to the polarized armature 150, then polarized armature 150 in the left-hand position, contact 151, conductor 152, caution light A² and to common battery. The circuit for displaying a "stop" signal is the same up to the armature 145 of the control relay R5AH, then along back contact 155, conductor 156, stop light A³ and to common battery. The circuit for displaying a "caution" signal by the signal mechanism B of the signal R5 extends from positive side of battery LB6, conductors 120, 144 and 171, armature 172 of the control relay R5BH, front contact 173, conductor 174, signal light B¹ to common battery. A circuit for displaying a "stop" signal by the mechanism B is the same as that just traced up to armature 172 of the control relay R5BH; then along back contact 175, conductor 176, signal light B² and to common battery. A circuit for displaying a "call-on" signal by the signal mechanism C of signal R5 is from battery LB6, conductors 120 and 191, armature 192 of the control relay R5CH, front contact 193, conductor 194, call-on signal light C¹ and to common battery. A circuit for displaying a "stop" signal by the call-on mechanism C of signal R5 is the same as that just traced up to armature 192, then back contact 195, conductor 196, signal light C² and to common battery. All signals similar to the signal R5 have signal light circuits similar to those just traced for signal R5.

Referring now to the signal R7 the circuit for the "proceed" light A¹ is from positive side of battery LB7 along conductor 253, armature 254 of the control relay R7AH, front contact 255, polarized armature 256 in the right-hand position, contact 259, conductor 260, signal light A¹, and to common battery. The circuit for the "caution" signal light A² is the same as that just traced up to the polarized armature 256, then with polarized armature 256 in the left-hand position, it extends along contact 257, conductor 258, caution light A², and to common battery. The circuit for the "stop" signal light A³ branches from the armature 254 in a down position, back contact 261, conductor 262, signal light A³, back to common battery. The circuit for the "call-on" signal C¹ of signal R7 is from battery LB7 along conductors 253 and 264, armature 265 of the control relay R7CH, front contact 266, conductor 284, signal light C¹, and to common battery. The "stop" light C² for signal R7 extends from the armature 265 of relay R7CH in a down position, back contact 268, conductor 289, signal light C², and to common battery. The circuit for the "proceed" signal light D¹ of the signal R7¹ extends from positive side of battery LB7 along conductors 253, 264 and 279, armature 280 of the control relay R7DH, front contact 281, polarized armature 282 in the right-hand position, contact 285, conductor 267, signal light D¹, and to common battery. The circuit for the "caution" light D² is the same as before up to polarized armature 282, then with armature 282 in the left-hand position, contact 283, signal light D²,

and to common battery. The circuit for the "stop" light D³ branches from the armature 280 along back contact 281, conductor 288, signal light D³, and to common battery. A circuit for the "call-on" signal light E¹ of the signal R7¹ branches from the conductor 279 and extends along conductor 289, armature 290 of the control relay R7EH, front contact 291, conductor 292, signal light E¹, and to common battery. A circuit for the "stop" light E² extends from armature 290 in a down position along back contact 293, conductor 294, signal light E² and to common battery.

In describing the operation, let us first assume that a train is to be allowed to proceed from the left to the right in the Fig. 2, taking the case where the dispatcher desires to have this train move from section Z past the siding P2 to the next passing siding P3, and where there is no other train occupying any of the intervening track sections. The dispatcher by energizing the dispatcher controlled relay R11HS raises the armatures 321 and 322 of the relay R11HS to disconnect the track relay TRT2 from the rails of the section T and to connect to these rails the track battery TB11, in the same manner as was described in connection with the circuits controlled by the relay R5HS. Current from the battery TB11 thus energizes the track relay TRT1 located at the left-hand end of the section T, and the energizing of the track relay TRT1 disconnects the track relay TRU2 from the rails of the section U and connects thereto the track battery TB10. The track battery TB10 will then, in turn, energize the track relay TRU1 located at the left-hand end of the section U. The track relay TRU1, in turn, disconnects the track relay TRV2 of section V, and connects to the track the track battery TB9, and the track battery TB9 will then energize the track relay TRV1. Now the energizing of the track relay TRT1 closed the circuit for the caution light of the automatic signal R10, and the energizing of the track relays TRU1 and TRV1 closed the proceed light circuits for automatic signals R9 and R8, respectively.

It will be seen, therefore, that signal R8 is controlled over a "tumble-down" circuit comprising a series of link circuits, of which one is illustrated in Fig. 3, there being a link circuit for each intermediate section for each direction. Thus the link circuits controlling signal R8 are the track circuits including relays TRT1, TRU1 and TRV1, respectively, the energization of the first link circuit being controlled by relay R11HS and that of each remaining link circuit by the relay of the next link circuit in advance. The circuits for the two directions are similarly arranged, and it follows that signal L11, which corresponds to signal R8 for traffic movements in the opposite direction, has a tumble-down circuit controlled by relay L8HS, the link circuits in this case being the track circuits which include relays TRV2, TRU2 and TRT2, respectively.

It will be readily apparent from the drawings that the link circuits are interlocked so that if one tumble-down circuit is energized all the links of the other tumble-down circuit are deenergized, back contacts of each relay such as TRU1, for example, being included in the circuit for the relay, such as TRV2, of the adjacent link circuit for the opposite direction.

Returning to the description of the operation, it is to be noted that the dispatcher upon energizing the relay R11HS also raised the arma-

ture 320 to close the circuit for the control relay R11AH in the same manner as was described in connection with the relay R5HS and the energizing of the relay R11AH closed the circuit for the 5 proceed or caution signal light of mechanism A of signal R11, and also reversed the polarity of the current supplied to the rails of section T to cause the indication of signal R10 to change from caution to proceed. Again, the energizing 10 of the track relay TRT1 also closed the circuit for the slow-releasing relay R10H, and likewise at signal R9, the energizing of the track relay TRU1 closed the circuit for the slow-releasing relay R9H. The despatcher after energizing relay R11HS must next energize the relay R7HS. Since relay TRV1 is now energized, the closing 15 of contact 221 of relay R7HS will cause the energization of relay R7AH to light lamp A1 so that signal R7 will indicate proceed. The lifting 20 of the armatures 321 and 328 of relay R7HS disconnects the track relay TRX2 from the right-hand end of the rails of the section X and connects thereto track battery TB7, with the result that the battery TB7 energizes the track relay 25 TRX1 located at the left-hand end of the section X. The despatcher will then next act to energize the relay R5HS, and the lifting of the armatures 231 and 233 of relay R5HS will disconnect the track relay TRZ2 from across the rails of the 30 track section Z, and to connect thereto the track battery TB5. Also, the energizing of the relay R5HS by the despatcher closes the control circuit for the relay R5AH at the contact 125. Relay R5AH will now be energized by the circuit traced 35 in connection with Fig. 6 and it will, in turn, close the "proceed" circuit to A1 of R5 with the result that a "proceed" signal is displayed by the mechanism A of the signal R5. The train can now proceed from the left-hand end of Fig. 2 to 40 the passing siding P3 at the right-hand end of Fig. 2 with a "proceed" signal displayed by each of the successive signals. It will be apparent that as the train proceeds and enters the successive track sections, that the signal at the entrance 45 of each section will display a "stop" signal to the rear of the train. It is to be noted that in the clearing of the signals for the movement of the train from the left to the right, that the circuits for all the opposing signals were opened 50 to thereby insure the display of a stop signal for an opposing train movement. Next let us assume that the despatcher wishes to permit a second train to follow this first train from the left to the right in Fig. 2. The despatcher by retaining the control relays R11HS, R7HS and R5HS 55 energized will cause the signals to the rear of the first train to clear as the first train advances. In connection with the clearing of the signals for this second train, it is to be noted that at the 60 intermediate signals, a permissive signal is given to the following train by means of the slow-releasing and stick relays. Taking, for example, signal R9, as the first train shunts the rails of the short section and drops the relay TR9, and then advances into the section U and shunts the 65 rails to deenergize the track relay TRU1, the stick relay R9S is energized by the pick-up circuit previously traced and which circuit passes through the back contact 301 of relay TR9, the back contact 298 of the relay TRU1, and the front contact 308 of the slow-release relay R9H, inasmuch as this circuit remains closed during the slow-release period of relay R9H. The stick 70 relay R9S is then retained energized through its own contact 312 and the back contact 298 of

the track relay TRU1. The energizing of this stick relay R9S acts to retain the track battery TB9 across the rails of the track section B by the closing of its front contacts 390 and 391, during the time that the track relay TRU1 is shunted by the train in the section U. The polarity with which the track battery TB9 is thus connected to section V is such as to reverse the track relay TRV1 and thereby cause the signal R8 to display a "caution" indication. 5

Next, let us assume that there is a first train to the left of the signal R5 and that it is moving to the right, that the dispatcher has deenergized relay R11HS and has energized relay L12HS and that there is a second train travelling to the 10 left from the passing siding P3 to the passing siding P2, and that the despatcher has reversed the switch SW3 in order that this second train moving from right to left may move into the passing siding P2 to clear the first train. The despatcher by energizing relay L8HS will cause the B mechanism of the signal L8 to display a "caution" signal, inasmuch as the KR3 relay is now reversed, and the energization of the relay L8HS will also connect the track battery TB8 across the rails at the left-hand end of the track section V, and then, in turn, battery will be connected at the left-hand end of each successive intermediate section, to thereby clear the L signals for the train approaching the passing siding P2 from the right. The despatcher, even though he energizes the relay R5HS, can not energize the control relay R5AH through the contact 125, inasmuch as there is no track battery connected across the rails of the section X, and thus the track relay TRX1 remains down to hold the circuit for R5AH open at front contact 127. However, the despatcher can advance the train moving from the left to the right past the signal R5 by energizing the control relay 2CHS. The 20 energizing of this relay 2CHS by the despatcher will place battery across the rails of section Z and will close the circuit for the control relay R5CH, and the energizing of the relay R5CH, in turn, will close the circuit for the "call-on" signal C1 at R5, with the result that the train from the left can advance to the signal R7 at which point it will receive a "stop" signal until the train moving from the right has passed into the passing siding P2 and the despatcher clears the R 25 signals. 30

The moving of a train from the right-hand end of Fig. 2 to the left-hand end will take place in a manner similar to that described in connection with the train travelling from the left to the right. It is to be noted that a train proceeding out of a passing siding will receive the same protection as the train advancing on the main track. To illustrate, a train on the passing siding P2 and moving to the right will receive the 35 same protection by the signal R71 as it would receive were it on the main track and advancing to the right past the signal R7. In switching in and out of any of the passing sidings, the despatcher has control of the movements through the 40 medium of his relay CHS and the "call-on" signals. 45

Although I have herein shown and described only one form of apparatus embodying my invention, it is understood that various changes and 50 modifications may be made therein within the scope of the appended claims without departing from the spirit and scope of my invention. 55

Having thus described my invention, what I 60 claim is: 70

1. In combination, a stretch of single track arranged in track sections; at least one of said track sections provided with two normally deenergized track circuits, one circuit associated with each direction of traffic; a signal normally indicating stop located at each end of the stretch to govern traffic in opposite directions through the stretch, a control circuit for each signal having two normally open contacts, means responsive to the energization of the track circuit associated with the direction of traffic which is governed by a signal for closing one of the said open contacts of the control circuit of that signal, a first means controlled from a central despatching office for closing the second open contact of said control circuit, a second means controlled from the central despatching office to effect the energization of the said track circuit, and means to prevent the energization of a track circuit unless the track circuit associated with the opposite direction of traffic remains deenergized.

2. In combination, a stretch of single track arranged in track sections; a plurality of track sections each provided with two normally deenergized track circuits each having a track relay, one circuit being associated with each direction of traffic; a signal normally indicating stop located at each end of the stretch to govern traffic in opposite directions through the stretch, a signal relay for each signal rendered effective to clear the respective signal upon the energization of all of the said track relays of the stretch associated with the direction of traffic which is governed by that signal, and means controlled from a central despatching office to bring about the energization of the said track relays, said means acting to first energize the most advance track circuit associated with the direction of traffic governed by the signal and then each successive track circuit in turn.

3. In combination, a stretch of single track arranged in track sections; a plurality of track sections each provided with two normally deenergized track circuits each having a track relay, one circuit being associated with each direction of traffic; a signal normally indicating stop located at each end of the stretch to govern traffic in opposite directions through the stretch, a signal relay for each signal rendered effective to clear its respective signal upon the energization of all of the said track relays of the stretch associated with the direction of traffic which is governed by that signal, means controlled from a central despatching office to bring about the energization of the said track relays associated with the direction of traffic governed by the signal, said means acting to first energize the most advance track circuit associated with direction of traffic governed by the signal, and then each successive track circuit in turn, and means to prevent the energization of a track relay unless the opposing track relay of the track section remains deenergized.

4. In combination, a stretch of railway over which traffic normally moves in both directions including a first passing siding, intervening track and a second passing siding, a signal to govern a train leaving the first passing siding for the second passing siding, and normally indicating stop, a second signal to govern a train leaving the second passing siding for the first passing siding and normally indicating stop; two sets of normally deenergized track circuits for said stretch, one set associated with each direction of traffic and adapted when energized to clear the signal

for the respective direction of traffic, and means controlled from a central despatching office to effect energization of one set or the other of said track circuits, said means acting to energize the most advance track circuit of the set and then each successive track circuit of said set.

5. In combination, a stretch of single track, signals located at intervals for governing traffic in one direction through the stretch and other signals located at intervals for governing traffic in the other direction through the stretch, a track relay for the control of each signal, a circuit for each track relay each of which circuits includes a front contact of the track relay for the next signal in advance governing traffic in the same direction, a branch for each track relay circuit around the front contact of the track relay which controls such circuit, and means controlled automatically by the direction of traffic for controlling each of said branches.

6. In combination, a stretch of single track, signals located at intervals for governing traffic in one direction through the stretch and other signals located at intervals for governing traffic in the other direction through the stretch, a track relay for the control of each signal, a circuit for each track relay each of which circuits is controlled by a front contact of the track relay for the next signal in advance governing traffic in the same direction, a branch for each track relay circuit which is not controlled by the front contact of the track relay which controls such circuit, and means controlled by traffic in the direction governed by the signal controlled by the track relay circuit to control said branch.

7. In combination, a stretch of single track, signals located at intervals for governing traffic in one direction through the stretch and other signals located at intervals for governing traffic in the other directions through the stretch, a track relay for the control of each signal, a circuit for each track relay each of which circuits includes a front contact of the track relay for the next signal in advance governing traffic in the same direction, a branch for each track relay circuit around the front contact of the track relay which controls such circuit, auxiliary relays for the control of said branches, and circuits for the control of said auxiliary relays controlled by said track relays.

8. In combination, a stretch of single track, signals located at intervals for governing traffic in one direction through the stretch and other signals located at intervals for governing traffic in the other direction through said stretch, a track relay for the control of each signal, a circuit for each track relay each of which circuits is energized in response to the energized condition of the track relay for the next signal in advance governing traffic in the same direction, and to the deenergized condition of the track relay for the opposing signal governing traffic in the other direction; a branch circuit for energizing each track relay circuit which is not responsive to the energized condition of track relay which controls such circuit, and means energized in response to traffic in the directions governed by the signal controlled by the track relay to control said branch.

9. In combination, a stretch of track, a first signal and a second signal for governing traffic in one direction over said stretch, a track relay for controlling each signal arranged that the signal indicates proceed when its track relay is energized, means for energizing the track

relay of the second signal when the track relay of the first signal is energized, and traffic controlled means for energizing the track relay of the second signal irrespective of the energization of the track relay of the first signal when a train travels in the direction for which said first and second signal governs traffic, but which means are ineffective to energize said track relay of the second signal when a train travels in the opposite direction.

10. In combination, a stretch of single track, signals located at intervals for governing traffic in one direction through the stretch and other signals located at intervals for governing traffic in the other direction through the stretch, a polarized track relay for the control of each signal and arranged to display a proceed indication when said relay is energized with one polarity of current and to display a caution indication when said relay is energized with the reverse polarity of current, a circuit for energizing each track relay with current of the first mentioned polarity each of which circuits includes a front neutral contact of the track relay for the next signal in advance governing traffic in the same direction, a branch for each track relay circuit which controls such circuit for energizing the said circuit with current of the reverse polarity, and means controlled by the traffic in the direction governed by the signal controlled by the track relay circuit for controlling said branch.

11. In combination, a single track railroad on which traffic moves in both directions arranged in track sections, an advance track section and a rear track section for a given direction of travel, a track relay for each track section arranged that the energization of the track relay for the rear track section is dependent upon the energization of the track relay of the advance track section, a signal to govern traffic through the rear track section in the given direction and adapted to indicate proceed upon the energization of the track relay of said rear section, and additional means to effect the energization of the track relay of said rear section irrespective of the track relay of the advance section when a train travels from the rear section into the advance section but which means is not effective when a train travels from the advance section into the rear section.

12. In combination, a railroad on which traffic moves in both directions arranged in track sections, an advance track section and a rear track section when considering a given direction of travel, a track circuit for each of said track sections having a source of current and a track relay and arranged that the circuit for the rear section includes a front contact of the relay of the circuit of the advance track section, a signal for said rear section adapted to indicate proceed in response to current flowing in the track relay of said rear section, and traffic controlled means responsive to a train passing from the rear track section into the advance track section to close the track circuit of the rear section around the front contact of the track relay of the advance section to thereby supply current to the circuit of the rear section and produce a caution signal indication, but which means is unresponsive to a train passing from the advance section into the rear section.

13. In combination, an advance track section and a rear track section, a track circuit including a track relay for each section, a slow release relay and a stick relay associated with the track

relay of the advance track section, and arranged that said slow release relay is energized when said track relay of the advance section is energized, a pick-up circuit for said stick relay including a front contact of said slow release relay and a back contact of said track relay, a holding circuit for said stick relay including its own front contact and a back contact of said track relay, means rendered effective to energize the track circuit of the rear track section when said stick relay is picked up, and a signal controlled by the track circuit of said rear section.

14. In combination, a stretch of track, a first signal and a second signal for governing traffic in one direction over said stretch; a polarized track relay for controlling each signal, arranged that the signal indicates proceed when its track relay is energized by one polarity, caution when said relay is energized by the reverse polarity and stop when said relay is deenergized; means rendered effective when the track relay of the first signal is energized to energize the track relay of the second signal with a polarity to produce a proceed signal indication, and traffic controlled means effective for energizing the track relay of the second signal with a polarity to produce a caution indication when a train travels in the direction for which said first and second signal governs traffic, but which means is ineffective to energize said track relay of the second signal when a train travels in the opposite direction.

15. In combination, a railroad on which traffic moves in both directions arranged in track sections, a first track section and a second track section, a track circuit for each of said track sections, means responsive to current in the track circuit of the first track section to establish the continuity of the track circuit of the second track section and to break the continuity of said circuit for the second section in response to the presence of a train in said first section, and traffic controlled means responsive to a train passing from the second track section into the first track section to establish the continuity of the said track circuit for the second track section irrespective of the first mentioned means, said traffic controlled means being unresponsive to establish the continuity of the circuit for said second section when a train passes from the first section into the second section, and a signal to control traffic through said second section and controlled by the said track circuit of the second section.

16. In combination, a portion of track, normally ineffective means located at each end of said portion of track for supplying track circuit current to the track, means controlled from a central despatching office to selectively render effective one of said means to supply current to the track, means controlled by traffic conditions on another portion of track to govern the polarity of the current supplied to the track, and signals to govern traffic through said portion of track controlled by the track circuit current thus supplied.

17. In combination, a portion of track, normally ineffective means located at each end of said portion of track for supplying track circuit current to said track, relays located at each end of said portion of track and controlled from a central despatching office to selectively render effective one of said means to supply current to the track, means controlled by traffic conditions on another portion of track to govern the polarity of the current supplied to the track, and

- signals to govern traffic through said portion of track controlled by the track circuit current thus supplied.
18. In combination, a portion of track, normally ineffective means located at each end of said portion of track for supplying track circuit current to the track, means controlled from a central despatching office to render effective the means at one end or the other of said portion of track to supply current to the track, means controlled by traffic conditions in advance of said portion of track to govern the polarity of the current supplied to the track, and signals to govern traffic through said portion of track controlled by the track circuit current thus supplied.
19. In combination, a portion of track, a battery located at each end of said portion of track for supplying track circuit current to the track and normally ineffective to supply current to the track, relays controlled from a central despatching office to selectively render effective one of said batteries to supply current to the track, a relay controlled by traffic conditions on another portion of track to govern the polarity of the current supplied by said battery, and signals to govern traffic through said portion of track controlled by the track circuit current thus supplied.
20. In combination, a track section, a normally deenergized track relay located at each end of said section, and each normally connected to the track, a battery located at each end of said track section to supply current to the track, but each normally ineffective to supply current, a dispatcher controlled relay associated with each end of the section, means controlled by each dispatcher controlled relay when energized to disconnect the track relay from the track at that end of the section and to render the battery located at that end of the section effective to supply current to the track to thereby energize the track relay located at the opposite end of the section, and signaling means under the control of the track relays.
21. In combination, an insulated track section over which traffic normally moves in both directions, signals to govern traffic in opposite directions through said section, each normally indicating stop; two normally deenergized track circuits for said section, one associated with the signal governing traffic in one direction and the other associated with the signal governing traffic in the opposite direction; a normally deenergized dispatcher controlled relay for each direction, and means controlled by each dispatcher controlled relay when energized to selectively energize the track circuit for the corresponding direction to thereby clear the signal with which said energized circuit is associated.
22. In combination, an insulated track section over which traffic normally moves in both directions, signals to govern traffic in the opposite directions through said section, each normally indicating stop, two normally deenergized polarized track circuits for said section, one associated with the signal governing traffic in one direction and the other associated with the signal governing traffic in the opposite direction; despatcher controlled means to selectively energize one of said track circuits, means controlled by traffic conditions in another track section to govern the polarity of the track circuit selected, said energization and polarity of said track circuit to effect a proceed indication of the signal with which said track circuit is selected.
23. In combination, an insulated track section over which traffic normally moves in both directions, signals to govern traffic in opposite directions through said section each normally indicating stop, two normally deenergized track circuits for said section, one for controlling the signal governing traffic in one direction and the other for controlling the signal governing traffic in the opposite direction, and manually controlled means associated with each end of the section effective when energized to selectively energize the track circuit associated with the signal at the opposite end of the section.
24. In combination, an insulated track section over which traffic normally moves in both directions, signals to govern traffic in opposite directions through said section, two normally deenergized track circuits for said section, one for controlling the signal governing traffic in one direction and the other for controlling the signal governing traffic in the opposite direction, and a despatcher controlled relay associated with each end of the section effective when energized to selectively energize the track circuit associated with the signal at the opposite end of the section.
25. In combination, an insulated track section over which traffic normally moves in both directions, signals to govern traffic in the opposite directions through said section, two normally deenergized polarized track circuits for said section, one associated with the signal governing traffic in one direction and the other associated with the signal governing traffic in the opposite direction, despatcher controlled means to selectively govern said signals and to selectively energize the track circuit associated with the signal selected, and automatically controlled means to govern the polarity of the track circuit selected.
26. In combination, an insulated track section over which traffic normally moves in both directions, two normally deenergized polarized track circuits associated with said track section, one for each direction of travel, despatcher controlled means to selectively energize the said track circuits of said section, automatically controlled means to govern the polarity of the track circuit selected, and a signal controlled by the said track circuit selected.
27. In combination, an insulated track section over which traffic normally moves in both directions, two normally deenergized polarized track circuits associated with said track section, one for each direction of travel, despatcher controlled means to selectively energize the said track circuits of said section, automatically controlled means to govern the polarity of the track circuit selected, and signals under the joint control of the despatcher controlled means and the track circuits.
28. In combination, traffic rails arranged in track sections, two normally deenergized track circuits for each track section including one for each direction each of which circuits includes the traffic rails in series, a relay manually controlled from a central despatching office for each direction, and means controlled by each said relay when energized to selectively energize the track circuits for the corresponding direction.
29. In combination, traffic rails arranged in track sections, two normally deenergized polarized track circuits for a track section each of which circuits includes the traffic rails in series, means controlled from a central despatching

office to selectively energize one or the other of said track circuits, and traffic controlled means to govern the polarity of the track circuit selected.

5 30. In combination, traffic rails arranged in track sections, two normally deenergized polarized track circuits for a given track section each of which circuits include the traffic rails in series, despatcher controlled means to selectively energize said track circuits, means controlled by traffic conditions in another track section to govern the polarity of the track circuit selected, and signals controlled by said track circuits.

15 31. In combination, traffic rails over which traffic normally moves in both directions arranged into insulated track sections, two normally deenergized polarized track circuits associated with a given track section, one for each direction of travel, despatcher controlled means to selectively energize the said track circuits of said given track section, automatic means under the control of traffic in another track section to govern the polarity of the track circuit selected, and signals under the joint control of the despatcher controlled means and said track circuits.

20 32. In combination, a stretch of railway over which traffic normally moves in both directions said stretch being divided into at least three track sections, a first signal normally indicating stop associated with each section to govern traffic in one direction, a second signal normally indicating stop associated with each section to govern traffic in the opposite direction; two means to control the clearing of each of the three or 35 more signals governing traffic in one direction, one means being a track circuit, and the second means being apparatus controlled from a central despatching office; and means to check the stop indication of the signals governing traffic in one direction through said stretch before the signals governing traffic in the opposite direction can be cleared.

25 33. In combination, a stretch of railway over which traffic normally moves in both directions and including a switch of a first passing siding, intermediate track and a switch of a second passing siding, said stretch being divided into at least three track sections, a first signal normally indicating stop for each section to govern traffic in one direction, a second signal normally indicating stop for each section to govern traffic in the opposite direction; two means to control the clearing of each of the three or more signals governing traffic in one direction one means being a track circuit, and the second means being apparatus controlled from a central despatching office; and means to check the stop indication of the signals governing traffic in one direction through said stretch before the signal governing traffic in the opposite direction can be cleared.

30 34. In combination, a stretch of railway over which traffic normally moves in both directions, a first set of signals located at intervals to govern the passage of trains through said stretch in one direction, a second set of signals located at intervals to govern the passage of trains through said stretch in the opposite direction, despatcher controlled means for selectively clearing either the first or the second set of signals, and traffic controlled means to check the stop indication of each of the signals of the opposing set before the signals of the set selected can be cleared.

35 35. In combination, a stretch of railway over which traffic normally moves in both directions,

a first set of signals located at intervals and each signal normally indicating stop to govern the passage of trains through said stretch in one direction, a second set of signals located at intervals and each signal normally indicating stop to govern the passage of trains through said stretch in the opposite direction, despatcher controlled means for selectively clearing either said first or second set of signals to permit the passage of a train, and traffic controlled means to check the stop indication of each of the signals of the opposing set before the signals of the set selected can be cleared. 5

36. In combination, a stretch of railway over which traffic normally moves in both directions, 15 said stretch being divided into at least three track sections; a signal at each end of each section, two normally deenergized track circuits for the intermediate section of said three sections, one track circuit when energized being effective 20 to clear the signals at one end of said section and at one end of the adjacent end section to permit a traffic movement in one direction, and the other track circuit when energized being effective 25 to clear the signals at the other end of said intermediate section and of the other end section to permit a traffic movement in the other direction; and means controlled from a central despatching 30 office to selectively energize either one or the other of the track circuits of said intermediate track section.

37. In combination, a first intermediate track section, a second intermediate track section, a track relay associated with the first track section and normally connected to the track, a track relay associated with the second track section and normally connected to the track, means for at times selectively energizing one track relay or the other, a source of power associated with both first and second track sections, means under 40 the control of the track relay for the first track section to disconnect the track relay for the second track section and to connect the source of power to said second section, means under the control of the track relay for the second track 45 section to disconnect the track relay for the first track section and to connect the source of power to said first section, a signal at each end of each section for governing traffic movements through the section, means for energizing the signal at 50 one end of a section when said source of power is applied to the track of the respective section, and means energizing the signal at the other end of a section when the track relay for the respective section is energized. 55

38. In combination, a first intermediate track section, a second intermediate track section, a track relay associated with the first track section and normally connected to the track, a track relay associated with the second track section 60 and normally connected to the track, means for at times selectively energizing one track relay or the other, a source of power associated with both first and second track sections, means under the control of the track relay for the first track 65 section to disconnect the track relay for the second track section and to connect the source of power to said second section, means under the control of the track relay for the second track section to disconnect the track relay for the first track 70 section and to connect the source of power to said first section, and a signal at each end of each section for governing traffic movements through the section, one said signal being under the control of the track relay for the section and 75

- the other said signal being under the control of said source of power.
39. In combination, a first intermediate track section, a second intermediate track section adjacent said first section, a track relay normally connected with the first track section, a track relay normally connected with the second track section, means for at times selectively energizing one track relay or the other, a source of power, means under the control of the track relay for the first track section to disconnect the relay for the second track section and to connect the source of power to said second section, means under the control of the track relay for the second track section to disconnect the track relay for the first track section and to connect the source of power to said first track section, and two signals located at the junction of said sections including a first signal under the control of the track relay for the first track section for governing traffic through said first section, and a second signal under the control of the track relay for the second track section for governing traffic through said second section.
40. In combination, a first intermediate track section, a second intermediate track section, a track relay for each of said track sections, a stick relay for each of said track sections, a source of current, means under the control of the track relay of the first track section for disconnecting, under certain traffic conditions, the track relay of the second track section and to connect the source of power thereto with a given polarity, means under the control of the stick relay of the first track section for disconnecting under certain other traffic conditions the track relay of the second track sections and to connect the source of power thereto with a polarity reversed to said given polarity, and a signal to govern traffic through said second track section controlled by the current thus supplied to said second track section.
41. In combination, a first intermediate track section, a second intermediate track section, a track relay for each of said track sections, a signal for each of said track sections to govern traffic through said sections; a first circuit, including a back contact of the track relay of the second track section, to connect the track relay of the first track section across the rails of said first section; a second circuit, including a back contact of the track relay of the first track section, to connect the track relay of the second track section across the rails of said second section; a proceed signal circuit, including a front contact of the track relay of the first track section, for the signal governing traffic through said first track section; and another proceed signal circuit, including a front contact of the track relay of the second track circuit for the signal governing traffic through said second track section.
42. In combination, a first track section, a second track section, a short track section located between said first and second track sections, a track relay for each of said three mentioned track sections and each normally connected to the track, means under the control of the track relay of the first track section for disconnecting under certain traffic conditions, the track relay of the second track section, means under the control of the track relay of the second track section for disconnecting, under certain other traffic conditions, the track relay of the first track section and means under the control of the track relay of the short

track section for controlling the connections of both the track relays for the first and second sections to their respective track sections.

43. In combination, a track section including a main section and a subsidiary section located at the entrance of said track section, a track relay for said main section, a track relay for said subsidiary section, a slow-release relay energized when both said track relays are energized, a stick relay, a pick-up circuit for said stick relay including a back contact of each of said track relays and a front contact of said slow-release relay, a holding circuit for said stick relay including its own front contact and a back contact of the track relay for the main section, and signaling means under the control of said stick relay.

44. In combination, a first passing siding, a second passing siding, a first track section and a second track section located between said passing sidings with their outside ends adjacent the passing sidings, a source of track current and a track relay located at each end of said track sections, two despatcher controlled relays including one at each siding each operable to selectively connect either the source of current or the track relay across the rails of the first and second track sections at their respective ends adjacent the sidings according as such relay is energized or deenergized, traffic controlled means to selectively connect either the source of current or the track relay across the rails of said track sections at their respective ends away from said sidings, and signaling means controlled by said track relays.

45. In combination, a stretch of railway including a first passing siding and intervening track and extending to a second passing siding, said stretch being arranged in track sections, each of which is provided with a normally deenergized track circuit, a signal to govern the movement of a train from the said first passing siding into said intervening track, means for clearing said signal upon the successive energization of all the normally deenergized track circuits existing between said second siding and said signal, and a despatcher controlled relay adjacent said second siding operable when energized to effect said successive energization of said track circuits.

46. In combination, a rear track section, a forward track section, a first signal located at the junction of said track sections to govern traffic through said forward track section, a second signal located to the rear of the rear track section to govern traffic through said rear track section, a normally deenergized track relay to control the first signal, a normally deenergized track circuit for the rear track section to control the second signal, and a despatcher controlled relay operable when energized to effect energization of said track relay to thereby clear said first signal and to effect energization of said track circuit to thereby clear said second signal.

47. In combination, a stretch of railway over which traffic normally moves in either direction, a first set of signals located at intervals to govern trains through the stretch in one direction, a second set of signals located at intervals to govern trains through the stretch in the opposite direction so arranged that there is a signal of the second set located adjacent each signal of the first set, despatcher controlled means to selectively control said first and second set of signals arranged to clear the signals of a set by starting at the remote end of the stretch and clearing the signals successively, and traffic controlled means to check the stop indication of the oppos-

ing signal adjacent each of the successive signals of the set selected before that signal can be cleared.

48. In combination, a stretch of railway over 5 which traffic normally moves in either direction, a first set of signals located at intervals to govern the passage of trains through the stretch in one direction, a second set of signals located at intervals to govern the passage of trains through said 10 stretch in the opposite direction, despatcher controlled means for selectively clearing either the first or second set of signals, and traffic controlled means to check the stop indication of each of the opposing set of signals before the final signal 15 of the selected set can be cleared.

49. A railway signal system including a stretch of railway, a first set of signals located at intervals to govern traffic in one direction through the stretch, a second set of signals located at 20 intervals to govern traffic in the opposite direction through the stretch, a track circuit for each signal responsive to traffic conditions in advance of the signal, and a manually controlled means to establish the direction of traffic adapted 25 to cooperate with the track circuits to selectively clear one or the other of said sets of signals and operating to clear the signals of the selected set by starting at the remote end and clearing the signals successively.

50. A railway signal system including, a stretch of railway, a first set of signals located at intervals to govern traffic in one direction through the stretch, a second set of signals located at 30 intervals to govern traffic in the opposite direction through the stretch, a track circuit for each signal responsive to traffic conditions in advance of the signal, and a manually controlled directional means adapted to also govern the track circuits to selectively clear one or the other of 35 said sets of signals and arranged to permit the manually controlled directional means to reverse the direction of traffic to the rear of a train as it occupies an intermediate point of the stretch and thereby permit traffic in the reverse direction 40 from said intermediate point.

51. A railway signal system including a stretch of railway, a first set of signals located at intervals to govern traffic in one direction through the stretch, a second set of signals located at intervals to govern traffic in the opposite direction through 45 the stretch, a control circuit for each signal responsive to traffic conditions in advance of the signal, and a manually controlled directional means adapted to cooperate with the control circuits to selectively clear one or the other of said sets of signals and arranged to clear the signals of the selected set by starting at the remote end of the stretch and clearing the signals successively and thereby permitting the reversing of 50 the direction of traffic to the rear of a train as it occupies an intermediate point of the stretch and the clearing of the opposing set of signals up to said intermediate point.

52. A railway signal system including, a stretch 55 of railway, a first set of signals located at intervals to govern traffic in one direction through the stretch, a second set of signals located at intervals to govern traffic in the other direction through the stretch, a track circuit for each signal responsive to traffic conditions in advance of the signal, and a manually controlled directional means adapted to also govern the track circuits to selectively clear one set or the other of said 60 set of signals and arranged to permit the manually controlled directional means to reverse the

direction of traffic to the rear of a train but not in advance of a train as it occupies any intermediate point of the stretch and thereby permit traffic in the reverse direction from said train but not towards said train.

53. A railway signal system including, a stretch of railway, a first set of signals located at intervals to govern traffic in one direction through the stretch, a second set of signals located at intervals to govern traffic in the opposite direction 10 through the stretch, a control circuit for each signal responsive to traffic conditions in advance of the signal and to the condition of the control circuit for the signal in advance, and a manually controlled means associated with each direction 15 of traffic each adapted to cooperate with the control circuit for the most remote signal of the corresponding set of signals to clear that signal and thereby clear each successive signal of the set serially.

54. In combination, a stretch of railway track provided with a traffic governing circuit connecting two traffic governing relays respectively associated with opposite directions of traffic and which circuit is normally short-circuited, a source of current associated with each direction of traffic for supplying current to said circuit but both normally disconnected therefrom, a signal normally indicating stop located at each end of the stretch to govern traffic in opposite directions 30 through the stretch, a control circuit for each signal having two normally open contacts, a first circuit controller governed from a central dispatching office for closing one of said open contacts of the control circuit for a signal, a second circuit controller governed from the central dispatching office for removing the short circuit of the traffic governing circuit and for connecting therewith the current source associated with the direction of traffic governed by said signal for 35 energizing the relay associated with that direction of traffic, and means controlled by said traffic governing relay when energized to close the other contact of the control circuit for said signal.

55. In combination, a stretch of railway track provided with a traffic governing circuit connecting two traffic governing relays respectively associated with opposite directions of traffic and which circuit is responsive to traffic conditions in 50 the stretch, a current source associated with each direction of traffic for supplying current to said circuit but both normally disconnected therefrom, a signal normally indicating stop located at each end of the stretch to govern traffic in opposite directions 55 through the stretch, a control circuit for each signal having two normally open contacts, means controlled by the energization of the traffic governing relay associated with the direction of traffic which is governed by a signal for closing one of said open contacts of the control circuit of that signal, a first means controlled from a central dispatching office for closing the second open contact of said control circuit, a second means controlled from the central dispatching office to connect the current source associated with the direction of traffic governed by that signal with the traffic governing circuit for energizing the associated traffic governing relay 60 and thereby establishing the direction of traffic, and means to prevent the central office dispatching means from establishing more than one direction for traffic at a time.

56. In a signaling system for single track rail- 75

roads, the combination with a single track section connecting two double track sections, of signals for governing traffic in one direction and signals for governing traffic in the other direction through said section, a relay for controlling each signal included in a circuit including a front contact of the relay for the next signal in advance and including a back contact of the relay for an adjacent signal governing traffic in the opposite direction, and manually controllable means for permitting relays controlling signals for governing traffic in one of said directions to be held at stop.

57. In a signaling system for single track railroads, the combination with a single track section connecting two double track sections, of signals for governing traffic in one direction and signals for governing traffic in the other direction through said section, a relay for each signal, a tumble down circuit for each direction of traffic comprising a plurality of link-circuits each link-circuit of which includes one of said relays and is controlled by the relay of the next link-circuit in advance, and means for interlocking each link 25 of one tumble-down circuit with one link of the other tumble-down circuit in such manner that if one tumble-down circuit is energized all the links of the other tumble-down circuit are de-energized.

58. In a signaling system for single track railroads, the combination with a single track section connecting two double track sections, of signals for governing traffic in one direction and signals for governing traffic in the other direction through said section, a relay for each signal, a tumble-down circuit for each direction of traffic each comprising successive link-circuits one for each relay and each link-circuit controlled by the next link circuit in advance, and means 35 for interlocking individually the link-circuits of said tumble-down circuits.

59. In a signaling system for single track railroads, the combination with a single track section connecting two double track sections, of signals for governing traffic in one direction and signals for governing traffic in the other direction through said section, a relay for each signal, a tumble-down circuit for each direction of

traffic each comprising successive link-circuits one for each relay and each link-circuit controlled by the next link-circuit in advance, means for interlocking the link-circuits individually of said tumble-down circuits, and means 5 for manually controlling said tumble-down circuits.

60. In a signaling system for single track railroads, the combination with a single track section connecting two double track sections, of signals for governing traffic in one direction and signals for governing traffic in the other direction through said section, a relay for each signal, a tumble-down circuit for each direction of traffic each comprising successive link-circuits one 15 for each relay and each link-circuit controlled by the next link-circuit in advance, and a back contact of the relay for one link circuit included in the adjacent link-circuit for the opposite direction of traffic.

61. In a signaling system for single track railroads, the combination with a single track section connecting two double track sections, of signals for governing traffic in one direction and signals for governing traffic in the other direction through said section, a relay for each signal, a tumble-down circuit for each direction of traffic each comprising successive link-circuits one for each relay and each link-circuit controlled by the next link circuit in advance, and means 30 for interlocking the link-circuit for one direction of traffic with the adjacent link-circuit for the opposite direction of traffic.

62. In a signaling system for single track railroads, the combination with a single track section connecting two double track sections, of signals for governing traffic in one direction and signals for governing traffic in the other direction through said section, a relay for each signal, a tumble-down circuit for each direction of traffic each comprising successive link-circuits one for each relay and each link-circuit controlled by the next link-circuit in advance, means 35 for interlocking the link-circuit for one direction of traffic with the adjacent link-circuit for the opposite direction of traffic, and other means 40 for interlocking said tumble-down circuits.

EARL M. ALLEN.
